CENTRIFUGAL SEPARATOR

Hans Olof Lindgren, Appelviken, Sweden, assignor to The De Laval Separator Company, New York, N. Y., a corporation of New Jersey

Application June 3, 1937, Serial No. 146,172
In Germany June 11, 1936

7 Claims. (Cl. 233—46)

This invention relates to centrifugal separators of the type in which the lighter liquid is discharged from the bowl by an axially symmetrical fixed paring device. Up to the present time, it has been common practice in such centrifuges to connect the discharge channel of the paring device directly to a fixed pipe line which must be disconnected each time the collecting vessel is to be tilted up for the purpose of cleaning the bowl. If the machine is used for the purification of a liquid, the sludge case of the bowl in some cases becomes filled with solid particles very quickly, the bowl having to be disassembled rather frequently for the removal of the deposited matter. To remove the discharge pipe from the paring device each time the bowl is disassembled is a troublesome and, in itself, unnecessary job.

According to the present invention, this inconvenience is avoided because the paring device which is fixed to a cover that is tiltably arranged over the bowl communicates directly with a channel which is provided in said cover and which communicates in known fashion through the hinged device of the cover with a fixed discharge pipe. With this arrangement it is no longer necessary to remove the fixed pipe from the paring device each time the bowl is disassembled. If the supply pipe also communicates in a similar manner through a channel provided in the cover with a supply nozzle projecting into the bowl, no pipe connections need be dismounted when the bowl is disassembled.

In the foregoing statement it was assumed that the centrifuge was a purifier and that, therefore, only one liquid leaves the bowl. When treating some kinds of material, for instance, transformer oil or lubricating oil, water is separated in addition to the solid particles which are deposited in the sludge space of the bowl. This water is generally discharged from the bowl as the heavier component. In centrifugal separators of the present type, it is advantageous to discharge the heavier component as usual through a level outlet or other more or less throttled free outlet channels. The heavier liquid leaving the bowl, for example, water, advantageously flows from a chamber, which is arranged in known manner in the cover and is provided with an outlet. As far as the water is concerned, no damage is caused if it is thrown out in atomized condition into the atmosphere surrounding the bowl. This is not the case, however, with the discharging lighter liquid when a transformer or lubricating oil is treated. Ow-

ing to the intimate contact with the air (the oil being thrown out in a very finely divided state) conditions are favorable for a quite rapid oxidation of the oil. It is, therefore, very important that it should be discharged from the bowl in such a manner that it enters far less into contact with the air. This result is effected by using a paring device of the type referred to above, which extends into the layer of liquid in the bowl.

The paring device, which can be removed from the centrifugal bowl only when this is dismounted, should be detachably connected with the cover provided above the bowl so that the device can be easily removed from the cover and can remain in the bowl when the cover is tilted up.

In centrifugal separators for purifying oils and the like it is necessary to have an arrangement which registers as soon as the sludge space of the bowl has become filled to such a degree with sludge that the purifying ability of the bowl is reduced, the pile of discs in this case being clogged by the sludge. In the open type of centrifuge, the registering was simply obtained in the following way. When the liquid being supplied could no longer flow the usual way owing to the accumulation of sludge, it overflowed the edge of the central tube of the bowl and was then usually collected in a special chamber in the cover of the centrifuge, and was then allowed to flow past a window or inspection glass or was made visible in some other way. In centrifuges of the present type in which the lighter liquid is discharged by a paring device projecting into the bowl, the central tube in the bowl must end below the paring device, and it is, therefore, very difficult to arrange an outlet for the purpose referred to at the upper part of the central tube. According to the present invention, this outlet is arranged instead in the bottom of the bowl and consists of a channel through which the chamber in the distributor communicates with the chamber surrounding the bowl. The channel advantageously begins in the immediate neighborhood of the spindle so that generally no liquid flows out therethrough. Only when the resistance to flow in the bowl has become sufficiently great, owing to the accumulation of sludge, will the liquid level in the distributor and in the overflow channel be displaced so far inwardly that liquid begins to discharge through the channel. This indicates that the bowl should be stopped for cleaning.

In order to remove the sludge from the sludge space, the bowl must be disassembled. It is, however, not necessary to dismount all the parts of

the bowl and the paring device, but it suffices to effect disassembly to such extent that all other parts may be removed from the bowl body, which remains in the frame of the machine. To take 5 apart the bowl top, the discs, the distributor and the paring device separately would be unnecessary work. In accordance with the present invention, after the lock ring of the bowl has been unscrewed it is possible to lift out all the parts 10 with the aid of the distributor, as they are all mounted on this central part. In order to facilitate the removal of the distributor it is, according to the present invention, provided with a threaded portion into which a lifting tool can 15 be inserted. This tool, which is advantageously arranged to press against the upper rim of the bowl body, must have a small diameter as it should be introduced into the supply nozzle, which is arranged in the center and fixed to the paring 20 device. According to the present invention the threads are, therefore, located on the conveyor wings of the distributor, the wings for this purpose extending toward the center of the bowl. Each wing is provided with teeth like a rack, 25 the teeth engaging with the threads of the tool.

The attainment of the above results and other 30 objects of the invention, relating particularly to details of construction, will become apparent from the following description read in conjunction with the accompanying drawing, in which the figure is an axial section through the improved separator.

40 is the body of the bowl of the centrifuge, 41 its removable top and 42 a lock ring by means 35 of which the top may be secured to the body.

1 and 2 are two chambers, respectively provided for the supply and for discharge of separated matter and are arranged in the cover 3 of the centrifuge. The chamber 1 communicates on one 40 side with a fixed supply pipe (not shown) through a channel 4 in the cover 3 and a hollow hinge 5, and on the other side with a supply nozzle 8 in the centrifuge through openings 6 in a sleeve 7. The chamber 2 communicates with the fixed discharge pipe (not shown) through a channel 9, 45 shown in dotted lines, in the cover 3, and a second hinge connection of the type previously described. On the other side, the chamber 2 communicates with a paring disc 13 through an annular chamber 10 and an annular channel 11 arranged in a part 12 which is detachably but tightly connected to the cover, the said paring 50 disc 13 projecting some way into the rotating mass of liquid contained in a paring chamber 14 which is arranged in the upper part of the bowl 55 top 42.

The sleeve 7 is provided with a hand wheel 15 by which it may be rotated, the threads 16 thereby causing the supply nozzle 8 to be pulled upwards. The nozzle 8 is tightly and rigidly fixed to the part 12, which has a conical shape and is provided with packing rings 17 and 18 lying in grooves and contacting with corresponding conical surfaces on the cover 3. The angle of the 60 sides of this cone with the center line is, as shown on the drawing, greater than the least angle of movement of the adjacent portion of the tiltable cover, thereby insuring immediate clearance when the cover begins to tilt. The nozzle 8 and the 65 paring disc 13 are thus detachably connected to the cover 3 and remain in the bowl when the hand wheel 15 is screwed upwardly and off. This is a necessary condition if the cover 3 is to be tilted upwardly on the hinge 5. After the cover has 70 been tilted up a threaded tool is introduced in

the nozzle 8 and screwed into the threads which are formed by a number of teeth 19 on the conveyor wings 20, and is thus engaged with the distributor 21 so that after removing the lock ring 42 of the bowl the distributor, with the aid of the 5 tool, can be lifted out of the bowl body together with the discs, the bowl top, the parer and the nozzle.

In the lower part of the bowl body a channel 23 extends through the bowl nave to the immediate 10 proximity of the spindle 24. The spindle is provided with a sleeve 25 which protects it from the action of the liquid discharged from the channel 23. Between the opening of the channel 23 in front of the spindle and the lining 25, there is a 15 chamber 26 which forms a continuation of the channel 23.

The discharge of the heavier liquid is controlled by a regulating disc 27. Instead of this disc, there might be provided the usual equivalents, 20 for example, a regulating screw or an outlet throttled by an adjustable screw or a replaceable nozzle.

If liquid should accidentally leak out of the 25 paring chamber 14, it is collected in the chamber 32 in the cover 3, whence it can be discharged 30 through the outlet spout 29, which may be provided with a cock as indicated. Any liquid leaking out at the tightening ring provided between the bowl top and the bowl body is collected in a chamber 30 arranged in the upper part of the bowl housing and provided with an outlet 31 which may or may not be provided with a cock. Any leakage at the places referred to is thus 35 shown by the fact that the liquid flows out of the outlets 29 or 31.

Clogging of the sludge space of the bowl is indicated by discharge of liquid through channel 23.

What I claim and desire to protect by Letters Patent is:

1. A centrifugal machine comprising a bowl and a paring chamber above and rotatable with the bowl, a machine frame, a cover hinged to said frame, a paring device positionable within the paring chamber, a supply nozzle and means, 45 independent of the cover and accessible from above the same and engaging the supply nozzle, to properly position the paring device within the paring chamber, said means being detachable to allow the cover to swing upward and, after the 50 cover is so lifted, permit the withdrawal of the supply nozzle and paring device.

2. A centrifugal machine comprising a bowl and a paring chamber above and rotatable with the bowl, a machine frame, a cover hinged to the 55 frame, a paring device adapted to enter the paring chamber, a supply nozzle which, with the paring device, is detachably supported from the cover, the paring device and cover having opposing surfaces adapted when contacted to form a 60 sealed joint, said joint being of a conical form of such wide angle that, when the nozzle and paring device are detached from the cover, lifting of the cover on its hinge causes immediate clearance at all points.

3. A centrifugal machine comprising a bowl and a paring chamber, a cover hinged to the frame on two hinged joints, a paring device adapted to enter the paring chamber, a supply nozzle which, with the paring device, is detachably supported from the cover, the paring device and cover having opposing surfaces adapted when contacted to form a sealed joint, said joint being of a conical form of such wide angle that, when the nozzle and paring device are detached 70 75

from the cover, lifting of the cover on its hinge causes immediate clearance at all points, the cover having passages and chambers providing communication respectively from one hinged joint to the supply nozzle and from the parer to the other hinged point.

4. A centrifugal machine comprising a bowl and a paring chamber above and rotatable with the bowl, a hinged cover, a central supply nozzle detachably carried by the cover and adjustable upward thereon, a paring device carried by the supply nozzle and forming therewith a unit, means providing passages in said cover for liquid flowing to said nozzle and for liquid removed by the paring device, said paring device and cover having opposed surfaces decreasing in diameter from the bottom to the top adapted, when contacted by upward adjustment of the nozzle, to form a joint of such wide angle that, when the nozzle with the paring device carried thereby is detached from the cover, swinging of the cover upward about its hinge causes immediate clearance at all points.

5. A centrifugal machine comprising a bowl, a hinged cover having a central opening, a hand wheel loose on said cover having a hub extending into said opening, a central supply nozzle detachably supported from said hub and movable upward by manipulation of the hand wheel, a paring device carried by the supply nozzle, the paring device and cover having opposing conical surfaces adapted to form a sealed joint when the supply nozzle is moved upward, the detachment of the hand wheel from the nozzle allowing the cover to swing out of engagement with the paring device.

6. A centrifugal machine comprising a bowl shell, its removable top and lock ring, a hinged cover, a central supply nozzle detachable from the cover, a paring device carried by said nozzle, a distributor extending into the bowl chamber, a set of discs carried by the distributor, said cover and paring device having opposed surfaces adapted when contacted to form a sealed joint, said joint being of a conical form of such wide angle that, when the nozzle is detached from the cover, lifting of the cover on its hinge causes immediate clearance at all points, said distributor being provided with tool-engageable means, thereby allowing a tool to be inserted through said nozzle into engagement with the distributor and, with the cover lifted and the lock ring removed, permit the distributor, the parer, the discs, and the bowl top to be handled as a unit.

7. A centrifugal machine comprising a bowl shell, its removable top and lock ring, a paring device, a supply nozzle carrying the paring device, a distributor extending into the bowl chamber, a set of discs carried by the distributor, a machine frame, a cover hinged to the frame, means, accessible from above the cover and engaging the supply nozzle, to properly position the paring device, said means being detachable to allow the cover to swing upward and allow the lock ring to be removed, said distributor being provided with tool-engaging means to thereby allow a tool to be inserted through said nozzle into engagement with the distributor and, after the cover is so swung upward and the lock ring removed, permit the distributor, the parer, the discs and the bowl top to be handled as a unit.

HANS OLOF LINDGREN.
